ELECTRIC SWITCH INDEXING MECHANISM

George Hegeman Hart, West Hartford, Conn.

Application June 5, 1937, Serial No. 146,620

7 Claims. (Cl. 74—527)

This invention relates generally to electric switches of the so-called "slow make and break" type and having an operating spindle provided with a handle adapted to be indexed to predetermined positions in order to selectively establish circuits.

In switches of this sort, it has been customary to provide an indexing mechanism for locating the switch in any of the several angular positions to which it may be shifted. This indexing mechanism frequently takes the form of a star wheel or plate provided with lobes and spring pressed members engaging against the periphery of the plate; the arrangement being such that when the star wheel is turned, the spring pressed members ride up the lobes, and when the apexes of the lobes pass the spring pressed members, the latter ride into the recess between the lobes. It is the aim of the present invention to provide certain improvements over this type of indexing mechanism and more particularly to provide an improved arrangement which will give the operator more or less the feel of a snap action such as is present in so-called "snap action" switches to assure him that the switch has been shifted to a desired position. My improved indexing mechanism is rendered more positive in its operation; there being a pronounced click when the switch is brought to its indexed positions, and sticking of the switch in intermediate positions is avoided.

It is a further aim of the invention to provide, in a switch of the character described, an improved arrangement through which the cams carried by the switch spindle operate the switch arms.

A further object of this invention resides in the provision of an electrical switch of the type described having various features of novelty and advantage and which is particularly characterized by its simplicity of construction, ease of assembly, economy of manufacture, and efficiency of operation.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawing:
Figure 1 is a longitudinal section through the switch showing its operating parts;

Fig. 2 is a cross section taken substantially along the line 2—2 of Fig. 1;

Fig. 3 is a cross section taken substantially along the line 3—3 of Fig. 1;

Fig. 4 is a bottom fragmentary view of the switch; and

Figs. 5, 6, and 7 are enlarged fragmentary views taken substantially along the line a—a of Fig. 1 and showing successive positions of the indexing mechanism while the switch is being shifted.

In accordance with this invention, there has been provided an electric switch having an operating spindle 10 rotatable in either direction to successive rest positions for operating one or more switch arms which are arranged to make and break desired circuits. The switch includes an indexing mechanism having a plurality of cooperating indexing cams or plates mounted on the spindle and engaged by spring pressed balls 20 or similar members which locate the switch in its operative or rest positions and oppose the initial spindle movement from one rest position to a successive rest position. After a predetermined initial spindle movement as controlled by a suitable operating member or handle, the indexing mechanism will cooperate with the handle to hasten the shaft rotation to the successive rest position and complete the spindle movement.

Referring to the drawing, there has been provided a casing 15 of suitable insulating material and having side walls 16 and 17 interconnected by a rear wall 18 and a bottom wall 19. The side walls and rear wall extend below the bottom wall, and a short front wall 20 is provided forming a cavity 20' on the under side of the switch within which are one or more switch arms. A cover 21 of suitable insulating material is secured in the outer end of this cavity, as by screws, to protect the switch arms within the cavity and provide access thereto. In the present showing, there is provided three switch arms 22, 23, and 24 which are respectively operated by tappets 22', 23', and 24' slidably mounted for free axial movement within bores passing through bottom wall 19 adjacent the switch arms. The tappets are supported by the switch arms and operated by cams, as will be later described.

The inner ends of the switch arms are rigidly secured to terminal plates 25 mounted on the casing and having screws 25' to facilitate electrical connections in a circuit. The free outer end of each switch arm has a suitable contact point P removably engageable with a similar contact point P on a suitable terminal plate 26 se-

cured to the casing and having connection screws 28'. In the present instance, the switch arms are shown as being inherently resilient and normally tending to assume closed circuit positions with the contact points in electrical engagement. However, it will be evident that the switch arms may be spring urged into closed positions in various other ways without deviating from the scope of the present invention. It will be further appreciated that the terminal plates may be suitably associated with one or more of the switch arms or contact points, dependent upon the circuits which the switch is adapted to control.

15. Casing 15 has its upper portion closed by a sheet metal cover 27 provided with a top wall 28 and front wall 28', thus forming a chamber 29 within the upper portion of the casing in which the cams and switch operating mechanism are mounted. The top and front cover walls are suitably received within rabbed portions of casing 15 and secured in position as by screws passing through the cover into rear wall 18 and as by screws passing through a bent over lip 28'' at the lower end of the front wall and into threaded holes 30 in the casing.

Spindle 10 which operates the switch mechanism is journalled at its forward end in a bearing 31 supported by the front-cover wall 28' and at its rearward end in a bracket 33 depending from and secured to top wall 28. Hence, the spindle and cam assembly and an indexing mechanism, to be later described, is removable as a unit with the cover to facilitate assembly and accessibility to the various switch parts. Bearing 31 projects forwardly from cover 27 and has external threads 31' receiving a nut 31'' so that the switch may be conveniently secured to a wall or panel in a single hole type of mounting. Spindle 10 extends forwardly from bearing 31 and has a suitable insulating handle 34 fastened thereon, as by a screw 35.

The tappets are respectively engaged and depressed by cams on spindle 10 so that rotation of the spindle to predetermined rest positions will operate the switch and establish desired circuits. In the present showing, there are provided three cams 22'', 23'', and 24'' rigidly secured to the spindle in spaced relation and respectively engageable with the tappets 22', 23', and 24' to control the opening and closing movements of the switch arms 22, 23, and 24. Each tappet has a partispherical head to facilitate a smooth engagement with its respective cam and to prevent the tappets from falling through the bores in the casing in which they freely move.

The indexing mechanism has an index member herein shown as spaced cams or plates 42 and 43 of duplicate contours and rigidly secured to spindle 10 within the casing and adjacent front wall 28'. An intermediate cam plate 44, generally similar to the index member is journalled on the spindle for limited rotary movement between plates 42 and 43. In the present instance, the switch is shown as having four operative positions so that the plates are each provided with four lobes and depressed portions respectively located between each pair of lobes. It will be appreciated, however, that the number of lobes and depressions on each plate is dependent solely on the number of positions to which the switch is to be shifted.

Plates 42 and 43, which have uniformly spaced duplicate symmetrical lobes 42' and uniformly spaced duplicate depressed portions 42'', are

rigidly secured to the shaft with their corresponding lobes and depressed portions in alignment. Intermediate plate 44 is generally similar in contour to plates 42 and 43 with the exception that the lobes 44' corresponding to lobes 42' are somewhat larger and of slightly greater radial extent from the axis of spindle 10. Plate 44 has depressed portions 44'' similarly spaced to depressions 42'' and at the same radial distance from the axis of spindle 10. This intermediate plate is lost motion connected to the index member (in the present instance, plate 43) as by pins 46 laterally projecting from plate 43 and received in arcuate slots 46' in plate 44. These slots are concentric with the spindle and permit a slight amount of rotary lost motion movement of the intermediate plate with respect to the plates at each side thereof. After the completion of this slight lost motion, all of the plates are constrained to rotate together as a unit.

A pair of spring pressed balls 48 received within opposed tubular portions 49 of a housing 50 are resiliently urged, as by springs 51, into simultaneous opposed engagement with the plate 25 contours, as shown in Figs. 5, 6, and 7. Housing 50, which may be suitably formed from metal bent to shape and secured to front wall 28', is centrally apertured to freely receive spindle 10 therethrough and to permit rotation of the index 30 plates. The ends of the tubular portions are provided with bent over ears 52 arranged to compressively secure the balls and spring assemblies in position. Since the depressed portions of the index plates are of corresponding size and correspondingly located, it will be appreciated that under normal conditions the balls will be received in opposed relation in similar depressed portions of each plate to secure the switch in its preset position.

When the spindle 10 is rotated in either direction, herein illustrated in a clockwise direction, plates 42 and 43 will integrally rotate with the spindle and the initial rotation of plate 44 will be retarded by the spring pressed engagement of the balls thereagainst. The peripheral contours of the lobes 44' are such that when the lost motion has been taken up by pins 46 within slots 46' (Fig. 7) lobes 44' will in effect constitute a smooth peripheral continuation of that portion of the lobes 42' engaged by the spring pressed balls, causing the balls to ride past and out of contact with lobes 42'. Hence, the initial rotational movement of spindle 10 and the index plates under influence of handle 34 will store up energy in springs 51 until the radial extremities of opposed lobes 44' engage balls 48, as shown in Fig. 7. Further movement of spindle 10 in the same direction will now cause the balls to ride downwardly on the other sides of the lobes 44' and into seated engagement with the next succeeding set of depressed portions to a position similar to that of Fig. 5 to again locate the switch in a rest position. The intermediate plate 44 being freely journalled on spindle 10, the pressure of the balls thereagainst will cause this plate to slip in the direction of spindle rotation after the balls move over the radial extremities of the lobes 44', resulting in a snapping action which produces an audible click and is felt by the operator to signal to him that the switch has shifted to the succeeding rest position.

It will thus be appreciated that the index plates cooperate with each other and with handle 75

34 to introduce a positive operation of the switch and to definitely position the switch when the handle is turned to shift the switch to its succeeding rest position. The switch cannot stick 5 in an intermediate position of its movement since the plates 43 and 44 are lost motion connected and the lobe of each plate has sharply sloping contours meeting at a point. Hence, the balls 48 will always tend to seat in depressed positions of the plates. Furthermore, the provision of tappets slidably mounted in the casing and engageable with the switch arms provides a substantial straight line movement of switch operation without producing undesirable wear or friction 10 frequently found in other types of switches.

As many changes could be made in the above construction and many apparently widely different embodiments of this invention could be made without departing from the scope thereof, it is 20 intended that all matter contained in the above description or shown in the accompanying drawings shall be interpreted as illustrative and not in a limiting sense.

It is also to be understood that the language 25 used in the following claims is intended to cover all of the generic and specific features of the invention herein described and all statements of the scope of the invention which, as a matter of language, might be said to fall therebetween.

30 I claim as my invention:

1. In an electric switch, indexing means comprising a rotary operating member, an indexing plate fixed to said member and having lobes with interposed depressions, a second indexing plate 35 on said member and having lobes corresponding to and of a greater radial extent than the lobes of said first plate, said second plate being adjacent said first plate and having a limited lost motion movement relative to said first plate and member, and a member resiliently urged against the perimeters of said plates.

2. In an electric switch, indexing means comprising a rotary operating member, index plates on said spindle having similarly positioned spaced lobes and depressed portions, one of said plates having limited rotary movement with respect to another of said plates fixed to said member, the lobes of said first plate extending beyond the corresponding lobes of said second 45 plate, and a member resiliently urged against said plate contours and normally seating within corresponding depressed portions of said plate to position the switch in indexed positions.

3. In an electric switch, indexing means comprising, a spindle rotatable in both directions, means responsive to the spindle rotation to operate the switch arm, an index plate rigidly secured to the spindle and having a plurality of spaced lobes and depressed portions, a second 55 plate generally similar in contour to the first plate and journaled on the spindle adjacent thereto, a lost motion connection between said plates, the lobes of said second plate radially extending beyond the lobes of the first plate, and a spring pressed member engageable with the contours of said plates whereby the lobes of said

plates will cooperate with said member to aid in rotating the spindle to successive predetermined positions after an initial spindle movement.

4. In an electric switch, indexing means comprising a spindle rotatable in either direction to 5 predetermined positions, adjacent generally similar index plates on said spindle and having similarly positioned spaced lobes and depressed portions, one of the plates being freely rotatable and the other being rigidly secured to the spindle, 10 one of said plates having an aperture therethrough receiving a pin laterally projecting from the other plate to provide a lost motion connection between the plates, said freely rotatable plate having lobes extending beyond the corresponding lobes of the other plate, and a spring pressed member engageable with the peripheries of said plates.

5. In an electric switch, indexing means comprising an operating spindle rotatable to predetermined positions, adjacent generally similar index plates on the spindle, one of the plates being freely rotatable, the other being fastened to the spindle; a lost motion connection between the plates, each plate having uniformly spaced 20 duplicate lobes and intervening depressed portions, said first plate having its lobes radially extending beyond the corresponding lobes of said second plate, and a spring pressed ball engageable with the peripheries of the plates. 30

6. In an electric switch, indexing means comprising an operating spindle rotatable to predetermined positions, a pair of adjacent index plates on the spindle and of generally similar contour, one of said plates being freely rotatable 35 and lost motion connected to the other which is rigidly secured to the spindle, each plate having uniformly spaced lobes and intervening depressed portions, said first plate having its lobes radially extending beyond the corresponding lobes of said 40 second plate, and a spring pressed member engageable with the plate peripheries, the contours of corresponding lobes engaged by the member being such that the contour of the engaged lobe of the first plate will serve as a continuation of the corresponding contour on the second plate. 45

7. In an electric switch, indexing means comprising an operating spindle rotatable in either direction to predetermined positions, a pair of fixed spaced index plates on the spindle and having duplicate aligned peripheral contours provided with uniformly spaced lobes and intervening depressed portions, an intermediate plate of generally similar peripheral contour journaled on the spindle between said other plates and lost motion connected to one of said other plates and having lobes radially extending beyond the corresponding lobes of said other plates, and a spring pressed ball engageable with the plate contours, the contour of the intermediate plate 60 engaged by the ball merging with and serving as a continuation of the corresponding contour of said other plates after the intermediate plate has been shifted to its lost motion position. 65

GEORGE HEGEMAN HART.
